[57] CLAIM

The ornamental design for compact fluorescent bulb socket, as shown and described.

DESCRIPTION

FIG. 1 is a perspective view of the compact fluorescent bulb socket of the present invention;

FIG. 2 is a right side elevational view of the compact fluorescent bulb socket;

FIG. 3 is a left side elevational view of the compact fluorescent bulb socket;

FIG. 4 is a top plan view of the compact fluorescent bulb socket;

FIG. 5 is a bottom plan view of the compact fluorescent bulb socket;

FIG. 6 is a rear elevational view of the compact fluorescent bulb socket; and,

FIG. 7 is a front elevational view of the compact fluorescent bulb socket.

The broken line showing throughout the drawing figures is included for the purpose of illustrating environmental structure only and forms no part of the claimed design.
